UNITED STATES PATENT OFFICE.

ELLEN LEACH, OF DILLON, MONTANA.

LAP-ROBE.

1,191,441.

Specification of Letters Patent. Patented July 18, 1916.

Application filed March 8, 1916. Serial No. 82,958.

To all whom it may concern:

Be it known that I, ELLEN LEACH, a citizen of the United States, residing at Dillon, in the county of Beaverhead and State of Montana, have invented certain new and useful Improvements in Lap-Robes, of which the following is a specification, reference being had to the accompanying drawings.

10 This invention relates to certain improvements in lap robes and it is an object of the invention to provide a novel and improved device of this general character which may be readily and effectively applied to the nether limbs and in such a manner as to effectively protect against elements.

15 It is also an object of the invention to provide a novel and improved lap robe provided with an opening through which the feet may be extended when the robe is employed by the occupant of a motor-driven vehicle.

20 The invention consists in the details of construction and in the combination and arrangement of the several parts of my improved lap robe whereby certain important advantages are attained and the device is rendered simpler, less expensive and otherwise more convenient and advantageous for use, all as will be hereinafter more fully set forth.

25 The novel features of the invention will hereinafter be definitely claimed.

30 In order that my invention may be the better understood, I will now proceed to describe the same with reference to the accompanying drawings, wherein—

35 Figure 1 is an inside view in open adjustment of a lap robe constructed in accordance with an embodiment of my invention; and Fig. 2 is a plan view illustrating my improved robe partly folded.

40 As herein disclosed, my improved lap robe comprises a body 1 of predetermined dimensions and formed of any suitable material and preferably rectangular in plan. The longitudinal margins of the body 1 intermediate their length are provided with the oppositely directed extensions or wings 2, and one end portion of the body 1 is adapted 45 to be folded transversely, as indicated at A, at a point slightly above the corresponding ends of the wings 2, and the outer margin of the returned portions 3 of the wings 2 are 50 permanently secured in folded position, as indicated at 4, and I have found it of par-

ticular advantage to provide the body 1 at the fold A and in close proximity to one of the wings 2, with the elongated transversely directed slot 5 through which the feet of a 60 person may be extended when the person employing the robe is operating a motor-driven vehicle.

65 As is thought to be clearly disclosed in the accompanying drawings, one end portion of the body 1 is adapted to be folded inwardly relative to the remainder of the body 1 and the opposite sides of said returned portion at a point inwardly of its side margins is provided with a series of alined spaced 70 fastening members 6, the members at one side being preferably studs and the members at the opposite side being preferably sockets.

75 One of the wings 2 adjacent its longitudinal margin is provided with the alined spaced sockets 7 adapted to coact with the studs of the returned portion of the body 1 when said wing 2 is folded inwardly to overlie the adjacent marginal portion of the 80 body 1, while the second wing 2 is provided with the alined studs 8 adapted to coact with the sockets arranged along the adjacent margin of the returned portion of the body 1 when said second wing 2 is caused to overlie 85 the body 1. By this arrangement it will be perceived that the nether limbs of a person are effectively inclosed by the lap robe and thereby fully protected against the elements.

90 I also have found it of advantage to provide the returned portion of the body 1 on its inner face and at substantially its transverse center, with the alined fastening members 9 herein disclosed as studs, adapted to operatively engage the fastening members 95 or sockets 10 secured to the inner face of the main portion of the body 1. By this arrangement it will be perceived that the robe will be caused to snugly engage the nether limbs of a person and will also, when the 100 robe is used in connection with two persons, permit one individual to remove the robe without interfering with the second person.

105 From the foregoing description, it is thought to be obvious that a lap robe constructed in accordance with my invention is of an extremely simple and comparatively inexpensive nature and is particularly well adapted for use by reason of the convenience and facility with which it may be assembled, and it will also be obvious that 110 my invention is susceptible of some change

and modification without material departure from the principles and spirit thereof and for this reason I do not wish to be understood as limiting myself to the precise arrangement and formation of the several parts herein shown in carrying out my invention in practice.

I claim:

1. A lap robe comprising an elongated body having oppositely directed wings formed intermediate of its side edges, one end portion of the body and the wings being returned, the returned portions of the wings being permanently connected to the wings proper, and coacting means carried by the returned portion of the body and the wings whereby said wings may be held in a position overlying the returned portion of the body, said body to one side of its transverse center being provided with a slit at the fold afforded by the returned portion of the body.
2. A lap robe comprising an elongated body having oppositely directed wings

formed intermediate of its side edges, one end portion of the body and the wings being returned, the returned portions of the wings being permanently connected to the wings proper, coacting means carried by the returned portion of the body and the wings whereby said wings may be held in a position overlying the returned portion of the body, and coacting fastening means carried by the inner face of the returned portion of the body and the inner face of the main portion of the body at substantially the transverse centers thereof for detachably connecting the main portion of the body and the returned portion of the body, said body to one side of its transverse center being provided with a slit at the fold afforded by the returned portion of the body.

In testimony whereof I hereunto affix my signature in the presence of two witnesses.

ELLEN LEACH.

Witnesses:

RICHARD R. PRICE,
MARGARET McALLISTER.
